K. YOSHINAGA

INKWELL COVER

Filed July 17, 1926

INVENTOR:
KUZO YOSHINAGA.

By Atty:

Edward M. Kojans

UNITED STATES PATENT OFFICE.

KUZO YOSHINAGA, OF LOS ANGELES, CALIFORNIA.

INKWELL COVER.

Application filed July 17, 1926. Serial No. 123,121.

This invention relates to a new and novel cover for ink-wells, ink-pots, and ink-bottles, and its objects are to provide a device of this character which will allow the pen 5 to receive, when inserted in the ink container, the proper amount of ink upon the tip or point of the pen, and to provide a cover which provides an auxiliary reservoir adapted to contain a limited amount of ink 10 for dipping the pen, and which protects, in a substantially closed reservoir, the main supply of the ink from loss by evaporation, and from becoming too thick for efficient use.

15 Another object is to provide a cover of this character in which the auxiliary font is automatically refilled by pressure of the pen as in dipping or inserting the pen therein, and in which the auxiliary supply is automatically replenished by means of suction from the main or reserve supply of ink within the container.

Other objects and advantages may appear in the subjoined detail description.

20 In the drawings, Figure 1 is a top plan and enlarged view of the ink-well cover embodying the present invention. Fig. 2 is a sectional elevation of the ink-well cover. Fig. 3 is a top plan view of the elastic suction bulb which serves to force the ink into the auxiliary font when the pen is dipped therein. Fig. 4 is a detail view of the upper valve which controls the flow of ink to the auxiliary font. Fig. 5 is a detail view of 25 the valve which controls the flow of ink from the main container into the intermediate suction passage beneath the auxiliary font. Fig. 6 is a perspective view of an ink-pot having my improved cover applied thereto.

Referring to the drawings in detail, the main body portion 11, of the ink-well cover, is provided with an enlarged annular top portion 12, having a central aperture 13, and a sliding lid 14 adapted to cover the dipping aperture 13. The body portion 11 is adapted to be inserted in the ink-pot 15, as shown in Fig. 6, or in a bottle, ink-well, or other ink container, as the case may be. 45 The body 11 has a central bore 16 which serves as the auxiliary font into which a pen 17 is to be dipped. In the annular top portion 12, I provide an annular compressible bulb 18, having a nipple 19 extending into a duct 20, which extends to a small suction chamber 21 at the base of body 11.

The suction chamber 21 is provided with a suction valve 22, and a capillary tube 23 extends from the body 11, and is adapted to depend into the ink which may be in the main container, the capillary tube 23, being controlled by suction valve 22 and having its open extremity 24 constantly immersed in the ink in the main container. A delivery port 25 is arranged between the suction chamber 21 and auxiliary font 16. To compress the bulb 18 when the pen is to be dipped into the ink in the auxiliary font, I provide a disk 26, having a central dipping aperture 27, the rim of which is adapted to be engaged by the pen as shown in Fig. 2. A float valve 28 is provided for the valve port 25, and is adapted to prevent the evaporation of the ink normally contained in the suction chamber 21. Valve member 22 has a weight portion 29, and valve member 28 has a weighted portion 30.

In use, the operation of my improved ink-well cover is as follows: Assuming the valve 22 and valve 28 to be seated on their respective valve seats, and the suction chamber to contain a supply of ink, and that the font 16 contains a supply of ink which is normally of a depth sufficient to cover the top of valve 28, and that the pen 17 is about to be dipped into the ink, then, on forcing the pen downwardly sufficiently to compress the bulb 18, the ink in the suction chamber is forced by the compressed air entering the chamber through duct 20, to pass through port 25 and into the font. The ink in the font becomes of sufficient depth to submerge the point of the pen. On withdrawing the pen, the bulb 18 expands to normal size, and the ink in the font and in the suction chamber will assume their normal level. The flow of the ink from the font and into the suction chamber beneath, will force the valve 28 to close valve port 25, and therefore only a portion of the ink is withdrawn into the suction chamber. As the valve 28 assumes its closed position, the further expansion of bulb 18 creates a suction and thereby draws a minute quantity of ink upward from the main container, and through tube 23 into the suction chamber, thereby replenishing the supply of ink in the suction chamber.

From the foregoing description and drawings, it may be seen that I have provided an efficient ink-well cover which provides an auxiliary font, capable of holding

a limited amount of the ink for dipping the pen, and having means for automatically replenishing the supply of ink in the font, from the main container, whenever the ink in the auxiliary font falls below its normal level or amount. With my improved device, a minimum supply of ink is maintained in the auxiliary font within the ink-well cover. On dipping the pen, an additional supply of ink from the suction chamber is immediately forced into the font, and sufficient to submerge the point of the pen.

What is claimed is:

1. In an ink-well cover, a body portion having a central font, a duct apart from the font, a valve port at the bottom of the font, and a suction chamber beneath the font and in communication with the duct and with the valve port, said body portion being adapted to fit in the mouth of an ink-well, an enlarged annular portion above the body portion, an elastic and compressible bulb disposed in the annular portion, a nipple integral with the bulb and extending into said duct, a disk disposed above the bulb to compress the bulb and adapted to be actuated by a pen, a capillary tube extending from the base of the body portion and into the main body of the ink-well, said tube having an open extremity and being in communication with said suction chamber, a valve member controlling the capillary tube, and a valve member adapted to close the valve port between the suction chamber and font.
2. In an ink-well cover, the combination with a body portion having a central auxiliary font, a valve port at the bottom of the font, a duct apart from the font, and a suction chamber beneath the font and in communication with the valve port and with the duct, of a capillary tube extending from the body and in communication with the suction chamber and having an open extremity adapted to be submerged in the main supply of the ink in the ink-well, a valve adapted to close the valve port between the suction chamber and capillary tube, another valve member adapted to close the valve port between the font and suction chamber, and means for forcing air into the duct on dipping a pen into the font.
3. In an ink-well cover, the combination with a body portion having a central font, a valve port at the bottom of the font, a suction chamber beneath the valve port and in communication therewith, and a separate duct leading from the suction chamber and upwardly and apart from the font, of a valve port at the bottom of the suction chamber, a capillary tube leading from the last-named valve port and adapted to depend into the main supply of ink, valve elements adapted to close said valve ports, and means for producing a suction in the suction chamber.
4. In an ink-well cover, a body portion having a central font, a suction chamber beneath the font, a valve interposed between the suction chamber and font, a capillary tube depending from the body portion and in communication with the suction chamber, a valve interposed between the suction chamber and the capillary tube, means actuated by the dipping of the pen into the font and serving to force the ink from the suction chamber into the font on downward movement of the pen, and to draw a minute quantity of the ink from the main container into the suction chamber on the upward movement of the pen.
5. In an ink-well cover, the combination with a body portion having a central font, a suction chamber beneath the font, a valve interposed between the suction chamber and the font, a duct leading from the suction chamber to the top of said body portion, a capillary tube depending from and in communication with the suction chamber, a valve interposed between the suction chamber and capillary tube, and an enlarged annular portion above the main body portion, of an elastic and compressible member disposed in the annular portion, a nipple on the compressible member and extending into the duct, and a compressing disk disposed above the compressible member and actuated by the dipping movement of the pen into the font.
6. In an ink-well cover, the combination with a body portion having a central auxiliary font, a suction chamber beneath the font, a valve interposed between the font and suction chamber, a tube depending from the body and in communication with the suction chamber, and a valve interposed between the tube and suction chamber, of means actuated by the dipping movement of the pen and serving to expel the contents of the suction chamber into the font on downward movement of the pen, and to draw a quantity of ink through the tube and into the suction chamber on the upward movement of the pen.
7. In an ink-well cover, a body portion adapted to be inserted in the mouth of the ink-well, and having an auxiliary font therein, a suction chamber beneath the font, a capillary tube depending from the suction chamber and into the ink supply in the ink-well, of valves disposed between the suction chamber and font and between the suction chamber and depending tube, and a suction member actuated by the movement of the pen and serving to force a quantity of ink from the main container of the well into the suction chamber and to force the ink from the suction chamber into the font.

In testimony whereof, I have hereunto affixed my signature.

KUZO YOSHINAGA.
